UNITED STATES PATENT OFFICE.

SIDNEY SMITH, OF CAMBRIDGE, MASSACHUSETTS.

GRATE.

SPECIFICATION forming part of Letters Patent No. 350,952, dated October 19, 1886.

Application filed January 23, 1884. Serial No. 118,435. (No model.)

To all whom it may concern.

Be it known that I, SIDNEY SMITH, of Cambridge, in the county of Middlesex and State of Massachusetts, have invented certain Improvements in Grates, of which the following is a specification.

This invention has for its object, first, to provide a grate having bars of sufficient strength to support the fuel and at the same time bring to the least possible amount of metal in contact with the fire; secondly, to provide a grate having a large amount of space for air, made up of the largest practicable number of subdivisions, so that the oxygen necessary for the combustion of the fuel—viz., eight pounds of oxygen to one pound of hydrogen, and sixteen pounds of oxygen to six pounds of carbon—shall be diffused throughout the entire area of the grate-surface; thirdly, to provide a grate-bar adapted to offer the minimum of resistance to the dropping of ashes and waste into the ash-pit; and, finally, to provide adjustable supports for the bearing-bars on which the grate-bars rest, and holding said bearing-bars in position without obstructing the draft or preventing the clearing of ashes and waste.

To these ends my invention consists in the several improvements, which I will now proceed to describe and claim.

Of the accompanying drawings, forming a part of this specification, Figure 1 represents a perspective view of a portion of a grate-bar constructed in accordance with my invention. Fig. 2 represents a longitudinal section of a furnace and ash-pit having my improved grate and its supporting device. Fig. 3 represents a section on line xx , Fig. 2. Fig. 4 represents an enlarged transverse section of one of the bars.

The same letters of reference indicate the same parts in all the figures.

Each of the bars a of my improved grate is composed of two longitudinal parallel drop-bars, 2 , joined at intervals by lateral bars 4 , of about half the depth of the longitudinal bars, and lateral wings 3 , projecting from the opposite outer faces of the longitudinal bars 2 , said lateral wings being gradually reduced in thickness from their upper to their lower edges, and also reduced in width from their upper to their lower edges, as shown in Fig. 4. bb represent the bearing-bars which support

the grate-bars a . At the points where the grate-bars rest on the bearing-bars two lateral wings, 5 , are extended as far at their lower as at their upper edges, and may project one-fourth of an inch beyond the wings 3 . Said wings 5 are of the same depth as the longitudinal bars. These extended wings 5 , by forming extended bearings on the bearing-bars, keep the grate-bars from rocking or turning from a perpendicular position, and by their projection beyond the other lateral wings of the grate-bars maintain a separation of about half an inch between each bar and the next, thus allowing of free passage of draft, and dropping of ashes and waste into the ash-pit. If preferred, however, the wings 5 may project no farther laterally than the wings 3 , so that all the wings of each bar will abut against all the wings of the next bar. A notch, e , in one end of each of the grate-bars at the point of contact with the bearing-bar supporting that end, prevents bodily endwise displacement of the bar, and thus maintains an open space at both ends of the grate-bars, and still allows of longitudinal expansion, the grate-bars being free to slip endwise on the other bearing-bars. The bearing-bars are of sufficient length to be built into the walls, and are recessed down on the upper side to receive the number of grate-bars forming the whole grate, the length of said recess being less by an inch or more than the entire width of the fire-box. The object of this recess is to keep the grate away from the walls of the fire-box by bringing the extended lateral wings referred to above in contact with the raised portions or shoulders g of the bearing-bar formed by the recess. The four extended lateral wings of each grate-bar, resting on the bearing-bars, form a continuous line of bearing for the grate across the whole width of the fire-box. The bearing-bars are supported in the center, maintained in an upright position, and prevented from warping and settling by a clasp or fork, c , of heavy iron, said clasp being welded to the upper extremity of a heavy perpendicular rod, c' . Said rod passes down through a proper rest, h , placed on the floor of the ash-pit. On the upper side of the rest is a heavy nut, k , turning on a thread cut in the end of said perpendicular rod, and enabling said rod and clasp to be vertically ad-

justed for the purpose of giving the clasp a perfect bearing on the bearing-bar. The vertical surfaces of the longitudinal bars 2 and wings 3 and 5 are polished, so that they will 5 offer the least possible resistance to ashes, cinders, &c., dropping between said wings.

I claim—

1. A grate-bar composed of the longitudinal bars 2, the lateral wings 3, formed as described, and the lateral wings 5, having extended lower edges combined with bearing-bars supporting the wings 5, as set forth.
2. The combination, with the series of grate-bars having lateral wings 5, of the bearing-bars set on the walls of the fire-box, and provided with shoulders near said walls, whereby the series of bars are confined laterally, and the outer bars of the series are prevented from coming in contact with the walls, as set forth.
3. The combination, with the grate-bars and

the bearing-bars supporting the same, of the clasps 6, supporting the central portions of the bearing-bars, and means for vertically adjusting said clasps to adapt them to the bearing-bars, as set forth.

4. The combination of a series of grate-bars and two or more bearing-bars engaged with the grate-bars, as described, so as to hold said bars laterally and the outer bars from contact 30 with the walls of the fire-box, one of said bearing-bars being also engaged with said grate-bars, as described, so as to prevent bodily longitudinal movement thereof.

In testimony whereof I have signed my name 35 to this specification, in the presence of two subscribing witnesses, this 21st day of January, 1884.

SIDNEY SMITH.
